CLAIM

The ornamental design for dispenser for dispensing a fluid into a nasal cavity, as shown and described.

DESCRIPTION

FIG. 1 is a perspective view from above of one side and one end of the dispenser;

FIG. 2 is a perspective view from below of opposite side and opposite end of the dispenser;

FIG. 3 is a perspective view from above of one side and one end of the dispenser, with parts separated;

FIG. 4 is a perspective view from below of opposite side and opposite end of the dispenser, with parts separated;

FIG. 5 is a side view of the dispenser;

FIG. 6 is an end view of the dispenser;

FIG. 7 is a plan view of the dispenser;

FIG. 8 is a side view of the dispenser, with parts separated;

FIG. 9 is an end view of the dispenser, with parts separated;

FIG. 10 is an opposite end view of the dispenser;

FIG. 11 is an opposite end view of the dispenser;

FIG. 12 is an underneath plan view of the dispenser;

FIG. 13 is an opposite side view of the dispenser, with parts separated;

FIG. 14 is an opposite end view of the dispenser, with parts separated; and,

FIG. 15 is side view of the dispenser, parts separated, and with lever shown in an alternative position.
